METHOD OF MAKING HEAT EXCHANGERS

Henry S. Holmes, Brooklyn, N. Y., assignor to
Metropolitan Engineering Company, Brook-
lyn, N. Y., a corporation of New York

Application March 13, 1936, Serial No. 68,605

2 Claims. (Cl. 29—157.3)

In boilers providing steam or hot water for the heating of houses, it is common to use fire tubes or passages enclosed within a water chamber, the hot gases of the furnace passing through such tubes so as to heat the water.

The present invention aims to provide a boiler in which tubes of this general character are of improved construction having a considerably enlarged heating surface; so that they may be fewer or smaller than the plain tubes which have heretofore been used. The invention also includes certain heat exchangers useful in boilers and various other applications; and also a method of producing them.

The accompanying drawings illustrate an embodiment of the invention.

Fig. 1 is a rear elevation of the complete boiler, partly in section. Fig. 2 is a longitudinal vertical section on a plane passing through two of the fire tubes. Figs. 3 and 4 are respectively horizontal sections on the lines 3—3 and 4—4 of Fig. 2. Fig. 5 is an end view of one of the fire tubes before installation. Figs. 6, 7, 8, 9 and 10 illustrate successive steps in a method of producing such tubes. Fig. 11 illustrates a modification of Fig. 6. Figs. 12, 13, 14 and 15 are cross-sections illustrating different methods of forming such tubes. Fig. 16 is an end view of a strip which is to be formed into a tube by the method of Fig. 15. Figs. 17 and 18 are respectively a cross-section of a method of forming another style of tube and an end view of such a tube. Figs. 19 to 22 illustrate partly and completely an alternative form of tube; Fig. 19 being a perspective of a tubular segment; Fig. 20 a perspective of the complete tube; Fig. 21 an elevation of the same, and Fig. 22 a section on the line 22—22 of Fig. 21.

Referring first to Figs. 1, 2 and 3, the boiler has a shell 1 extending from top to bottom and a dome 2. Within the lower part is the casing 3 of the furnace, small enough to leave between itself and the outer casing a water leg 4 of annular shape constituting the upper part of the furnace and communicating with the water chamber above. Any usual or suitable kind of furnace may be provided, burning either solid fuel or oil or gas. At the front is a door 5 used for coal firing. Gas or oil burners would normally be placed at the bottom of the combustion chamber formed by the inner casing 3. At the top is a coupling 6 for the steam or hot water outlet, and at the bottom a coupling 7 for the return pipe bringing condensed steam or feed water. Tubular couplings 8 and 9 serve for attachment of pressure gauge and pressure regulator. Various other attachments and common details are assumed.

The furnace has an arched portion 10 at the front and an arched portion 11 at the rear, these

two being connected by a vertical plate 12 extending across the furnace from right to left. Into plate 12 are swaged or otherwise connected the rear ends of fire tubes 13 which extend forward to a smoke box 14 normally covered at the front end, the cover being removable to facilitate cleaning. The back wall 15 of the smoke box carries the swaged or welded forward ends of the lower tier of tubes 13 and the similarly connected forward ends of an upper tier of fire tubes 16 which lead entirely through the water chamber to the back of the boiler into a smoke hood 17 whence the flue gases are conducted in any usual or suitable way to a stack or chimney.

In order to increase the efficiency of such fire tubes for use in this and in various other types of boiler and other heat exchangers, I propose to make these tubes of a special construction by which an increased heating surface is secured for a given size and number of tubes. These are made of sheet metal with inward projections welded to the inner face. While such tubes are specially useful because of their compactness in boilers and the like, they are also useful as heat exchangers in various other apparatus. Several methods of producing such tubes are illustrated in Figs. 5 to 22.

Referring to Figs. 5 and 6, the shell of the tube is made of two strips of sheet metal 18 of semi-circular shape welded together along edges 19. Projections 20 are welded to the inner faces of the strips and extend into the interior. The method of production is as follows:

A flat sheet 18, Fig. 6, has the projections 20 welded to one face of it. The projections are arranged in lines so as to constitute a sort of longitudinal fins on the face of the strip. But each of the projections is fairly small in cross-section and is separately welded to the strip, thus avoiding strains which occur from the heat of welding continuous fins of substantial length.

There are three such fins or lines of projections shown in Fig. 6, but the number may be suited to the size and proposed use. The length of the projections is such as to extend nearly to the center of the tube so that they practically or nearly cover the entire diameter and thus utilize the stream of hot gas throughout practically its entire cross-section; transmitting the heat rapidly through the welded joint to the shell of the tube and thence to the water outside.

The projections are so grouped as to leave open transverse spaces 21 extending clear across the strip and also to leave clear transverse spaces 22 at the ends. The strip of Figs. 6 and 7 is bent down into a hollow shape such as the illustrated semi-cylindrical segment by means of a die 23, Fig. 8, having a semi-circular recess and a punch 24, the underface of which is shown in Fig. 9. It has semi-circular projections 25 on 60

the ends and 26 located to fit in the transverse spaces 21 between the projections so that it can pass between those projections and bend the strip 18 in the manner of Fig. 8, with the projections 20 extending inward substantially radially.

5 After this operation the finishing operation may be performed in order to straighten the edges by means of a second punch 27, Fig. 10, which engages only the edge portions 28 of the 10 strips 18. Two of such semi-cylindrical segments are brought together as in Fig. 5 and may be welded accurately and quickly by resistance welding between suitable electrodes. Or various other methods of welding may be utilized.

15 The projections 20 instead of being in a line parallel with the sides of the strip, and ultimately with the central axis of the tube, may be set in oblique lines as in Fig. 11, leaving clear transverse spaces 21 as before for part of a 20 punch. A tube made of such strips will differ from Fig. 5 only in that the lines of projections will be spiral instead of truly axial and will thus tend to secure better contact with the stream of hot gas.

25 Fig. 12 shows another method of pressing the strip 18 with its projections 20 into the die 23. The punch 29 is provided with a long rib 30 which engages the central line of projections 20 and pushes these and consequently the entire strip 30 18 down into the die.

35 According to Fig. 13 the punch 31 differs in that it has a rib 32 in the lower end of which is a slot that accommodates the center line of projections 20 while pressing the strip 18 down into the semi-circular die.

40 Fig. 14 illustrates an extension of the idea of Fig. 13, using a punch 33 which has a rib 34 with a rounded enlargement 35 on the end having a slot for the central line of projections 20, the 45 sides of the enlargement 35 being cut away to permit the bending in of the projections 20 at the sides. This has the advantage of giving a curved bearing face on the inside of the work during the bending operation.

45 Figs. 15 and 16 show how the punch and die of Fig. 14 may be used to make a tube which is composed of a single strip of metal 36. The strip is made of a width corresponding substantially to the entire circumference of the tube. It has five lines of projections 20. The central one is 50 engaged in the slot in the enlargement 35 at the lower end of the die. The upper part of the rib 34 is sufficiently small to permit the ends of the strip 36 to be bent nearly together. The strip before being inserted is of the hollow shape 55 shown in Fig. 16. The central portion is left flat with the three corresponding projections 20 standing upright. The ends are curved around about a quarter circle. The strip is then introduced into the die and punched as in Fig. 15 to 60 the hollow, nearly tubular, shape there illustrated. The punch is then withdrawn.

65 In this case, as in Fig. 14, the punch must be withdrawn lengthwise of the tube because of the interference of the bent-in projections 20 at the sides. The strip 36 is then pressed between electrodes to bring its two free edges together and to weld them so as to form the complete tube.

70 The shape of the tube in cross-section is not necessarily circular. Rectangular shapes have some advantage in compactness and may be used where the pressures involved are not sufficient to distort the cross-section.

According to Fig. 17 a strip 37 is made with

three rows of projections and is then bent down in a die 38 by means of a punch 39 having a recess in the lower end to accommodate the projections; thus bending the strip into a segment or hollow shape of channel form. Two such segments 37 are united by means of welded edges 40 and will have the projections 20 extending in parallel directions from two opposite walls of the tube nearly to the center thereof.

10 In the designs of Figs. 12, 13, 14, 15 and 17 it is not necessary to leave transverse spaces (such as 21, Figs. 6 and 11) for punch segments; therefore, pins 20 may be provided in continuous rows and as close together as required.

15 The strip may be first formed up into a semi-cylindrical or other segment of a tube before welding in the projections; subsequently uniting the tubular segments, as explained. In that case, the projections may be differently shaped and arranged since there is no necessity for leaving 20 spaces to accommodate a bending punch.

25 Figs. 19 to 22 illustrate such a tube and the method of production. One of the hollow semi-circular segments 41, Fig. 19, is provided with projections 42 which are in the form of inclined baffles, parallel to each other so as to leave between them an oblique channel 43.

30 It will be understood that a number of such baffles and channels are provided according to the length of the tube. The baffles are curved at 35 their rear edges to fit the curved segment 41 and have their outer edges lying in a diametral plane. Two such strips with baffles welded within them are placed together as in Fig. 20, one being inverted end for end with reference to the other 40 so that the baffles at one side will be as indicated at 42 and those at the other as indicated at 42'. The segments are then welded together as at 44. The gases will thus travel along the tube continuously forward first in the channel between two baffles 42 at one side and then (dividing into two streams) between the baffles 42' at the opposite side; and so on throughout the length of the tube. This arrangement secures a complete wiping of the faces of the baffles by the hot gas 45 and forces the latter into a zig-zag path in which the stream is divided again and again.

50 Various other modifications in detail may be made by those skilled in the art without departing from the invention as defined in the appended claims.

Various modifications may be made by those skilled in the art without departing from the invention as defined in the following claims.

What I claim is:

1. The method of making a heat exchanger of the character described which comprises welding projections along the length of a strip of sheet metal, leaving open transverse spaces, bending said strip to hollow form with the projections extending inward by pressure against the strip at said open transverse spaces and welding the edges of such strips together.

2. The method of making a heat exchanger of the character described which comprises welding projections along the length of a strip of sheet metal to form discontinuous longitudinally extending ribs, bending said strip to a hollow form with the projections extending inwardly by applying pressure against said strip between said projections and welding the longitudinal edges 70 of such strip to form a hollow structure.
